Primary Examiner—Holly Baynham*Attorney, Agent, or Firm*—Roylance, Abrams, Berdo & Goodman, LLP[57] **CLAIM**

The ornamental design for a high density polystyrene spacer for stacking warehouse materials, as shown and described herein.

DESCRIPTION

FIG. 1 is a perspective view of a high density polystyrene spacer in accordance with a first embodiment of my new design.

FIG. 2 is a front side elevational view of the spacer illustrated in FIG. 1 in accordance with a first embodiment of my new design;

FIG. 3 is a rear side elevational view of the spacer illustrated in Figs. 1 and 2 in accordance with a first embodiment of my new design;

FIG. 4 is a top plan view of the spacer illustrated in Figs. 1-3 in accordance with a first embodiment of my new design; FIG. 5 is a bottom plan view of the spacer illustrated in Figs. 1-4 in accordance with a first embodiment of my new design;

FIG. 6 is a left and elevational view of the spacer illustrated in Figs. 1-5 in accordance with a first embodiment of my new design;

FIG. 7 is a right end elevational view of the spacer illustrated in Figs. 1-6 in accordance with a first embodiment of my new design;

FIG. 8 is a perspective view of a high density polystyrene space in accordance with a second embodiment of my new design;

FIG. 9 is a front side elevational view of the spacer illustrated in FIG. 8 in accordance with a second embodiment of my new design;

FIG. 10 is a rear side elevational view of the spacer illustrated in Figs. 8 and 9 in accordance with a second embodiment of my new design;

FIG. 11 is a top plan view of the spacer illustrated in Figs. 8-10 in accordance with a second embodiment of my new design;

FIG. 12 is a bottom plan view of the spacer illustrated in Figs. 8-11 in accordance with a second embodiment of my new design;

FIG. 13 is a left end elevational view of the large end of the spacer illustrated in Figs. 8-12 in accordance with a second embodiment of my new design; and,

FIG. 14 is a right end elevational view of the small end of the spacer illustrated in Figs. 8-13 in accordance with a second embodiment of my new design.
